UNITED STATES PATENT OFFICE.

JESSE W. RENO, OF NEW YORK, N. Y.

FIRE-PARTITION.

SPECIFICATION forming part of Letters Patent No. 760,484, dated May 24, 1904.

Application filed September 17, 1903. Serial No. 173,617. (No model.)

To all whom it may concern:

Be it known that I, JESSE W. RENO, a citizen of the United States of America, and a resident of the city, county, and State of New York, 5 have invented certain new and useful Improvements in Fire-Partitions, of which the following is a specification.

My invention relates to fire-partitions—that is, to partitions which are adapted to close communication between compartments which they divide to prevent the communication of smoke or fire, and which partitions are normally open for the free communication of light and air.

My invention is designed especially to meet the requirements of elevator-shafts. Such shafts are usually partitioned off by means of open metal work or grilles, which under normal conditions afford adequate protection for the elevator-shaft and permit the entrance of 10 light and air, but which, in case of fire, form no barrier to the passage of smoke and flame into the elevator-shaft and from one story to another. The elevator-shaft, in fact, in cases of fire often becomes a veritable chimney, 15 causing a draft which greatly increases the rapidity of the spread of fire. In many cases where the elevators might otherwise be of the greatest service in saving life and property during the early stages of a fire their use is 20 made impossible on account of the smoke which finds its way into the elevator-shaft. In many cases, as in large department-stores, a small fire upon one floor may cause immense damage to goods and even loss of life on other 25 floors merely because of the smoke which travels up the elevator-shaft from the floor on which the fire is located.

It is the object of my invention to provide a partition especially applicable to elevator-shafts which under ordinary circumstances, 30 as during business hours, may be open for the free and convenient passage of light and air, and which during times when the building is not occupied and in case of fire may be closed, 35 so as to be practically air-tight, and thus prevent the formation of strong drafts of air, smoke, or fire in the elevator-shaft, and effectually prevent the passage of smoke from one story to another.

50 My invention consists in forming a parti-

tion, preferably of non-combustible material, of two or more layers or thicknesses movable with reference to each other and perforated by openings which may be brought into register to permit the passage of light and air 55 and which may be moved or shifted relative to each other to close said perforations.

My invention consists, further, in novel arrangements and details of construction to be 60 hereinafter more fully described.

In the drawings accompanying and forming part of this specification, Figure 1 represents a portion of an elevator-shaft provided with the preferred form of my invention. Fig. 2 represents a section of an elevator-shaft provided with means for operating the partitions on three sides from a single point. Fig. 3 is an enlarged view of a panel of an elevator-shaft provided with my invention. Fig. 4 is a section on line *a a* of Fig. 3. Fig. 5 is a 65 modified form of my invention in which more than two plates are used. Fig. 6 is a section on line *b b* of Fig. 5, and Fig. 7 is a similar section showing the partition closed.

The reference characters are used in the 70 same sense in the drawings and the specification.

Numerical 1 represents a section of an elevator-shaft between the two floors 2 and 3. Elevator-shafts are usually rectangular in form, 75 and the sides are generally composed of a lower imperforate panel extending part way up from the floor, and an upper panel 4, which during normal conditions, when the elevator is in use, it is desirable to have open for the 80 free passage of light and air.

5 represents a fixed partition-plate made 85 preferably of sheet metal and secured in any convenient manner to the framework of the elevator-shaft and provided with perforations 90 or openings 6 of convenient size.

7 represents a movable partition-plate slidably mounted on the plate 5, having perforations or openings 8 of the same size and shape as the perforations 6 in plate 5, with which 95 they are adapted to register when the fire-partition is open. The plate 7 is also provided with parallel slots 9, in which are received the rivets 36, which pass through said slots and are fixed in the plate 5. The plates 100

7 are thus secured to the plates 5, but are permitted to have a movement on said plates transversely to the longitudinal axis of the openings 8.

5 10 represents racks secured to the plates 7 and adapted to engage the gear-wheels 11, mounted on the shaft 12. The shaft 12 is mounted in bearings 13. During part of the circumference of the gear-wheels 11 ratchet-teeth 14 are provided, which are adapted to be engaged by the pawl 15. The pawl 15 is provided with the lug 16, which acts as an armature for the magnet 17.

18 represents a lever secured to the shaft 12, and 19 a chain secured to the lever 18.

20 20 represents springs secured to the movable plate 7, which act upon said plate to move it in a direction to close the openings 8.

Ordinarily only three sides of the elevator-shaft will be provided with my fire-partition, as the remaining side will be controlled by the ordinary elevator-doors, which, however, are imperforate, so as to prevent the passage of smoke and air through said doors when 25 they are closed, or these doors may themselves be provided with my improved fire-partition.

The operation of my improvements is as follows: During the ordinary use of the elevator 30 the parts will be in a position shown in Figs. 1, 3, and 4—that is, the movable plate 7 will be in a position in which the openings therein register with the openings in the fixed plate 5. When, however, it is desired to close the 35 partition, the pawl 15 is released from the ratchet 14, and the springs 20 act upon the movable plate 7, causing it to close the openings in the partition. The pawl 15 may be operated by hand, or it may be operated by 40 the magnet 17, and the magnet 17 may be controlled by a push-button located in any convenient place, or it may be controlled by a thermostat in a manner that is well understood. When it is desired to open the partition, the chain 19 is pulled down and the plate 45 7 raised to the position shown in Figs. 3 and 4.

In Fig. 2 I have illustrated a means for operating the fire-partitions on the several sides of the elevator-shaft simultaneously. These 50 means consist in the shafts 21, 22, and 23 and provided with bevel-gears 24, fixed to the ends of said shafts and engaging each other, so as to cause all of the shafts to operate in unison.

In the construction shown in Figs. 5, 6, and 55 7 a single stationary partition-plate 25 is provided with openings 26, which are substantially twice the width of the imperforate portions 27 between said openings. Two movable partition-plates 28 and 29, each having 60 openings of the same size and shape as those of the stationary plate 25, are slidably mounted on said stationary plate and preferably mounted, respectively, on either side of said plate. 30 represents a shaft mounted in bearings 65 fixed to the framework of the elevator-

shaft. 31 represents sprocket-wheels fixed to said shaft, which are engaged by the sprocket-chains 32, one end of each of said chains being fixed to the movable plate 28 and the other end to the movable plate 29. From this construction it is obvious that as the shaft 30 is rotated the plates 28 and 29 will be caused to move in opposite directions either to open or close the perforations or openings 26 in the fixed partition-plate. By means of this construction I am enabled to increase relatively the size of the openings in the partition, which, under some circumstances, may be desirable, and it is obvious that the relative size of the openings may be still further increased by a further increase in the number of plates employed.

Where three plates are used, the width of the opening is two times the width of the bar. Where four plates are used, it is three times, 85 and so on, the width of the opening in each case being substantially equal to the number of plates less one multiplied by the width of the bar.

In the cross-sectional view in Fig. 6 the 90 openings are shown fully uncovered or the partition fully open. In Fig. 7 the partition is shown fully closed. For convenience of illustration the thickness of the plates, as shown in the drawings, is relatively much 95 greater than would occur in practice, and when the plates are closed a small opening 33 is shown still to exist. This opening, however, in practice is relatively so small as to be of comparatively slight importance. Even this 100 opening may, however, be reduced or eliminated by a slight offset in the edge 34 of the plate 29 or the edge 35 of the plate 28 or offsets in the edges of both plates.

It is obvious that the contours of the openings in the plates may be changed in a variety of ways and that the particular mechanism for operating the movable plates either automatically or manually may be varied without departing from the spirit and scope 105 of my invention.

Having thus described my invention, what I claim is—

1. In an elevator-shaft, the combination with fixed perforated partitions arranged upon a plurality of the sides of the elevator-shaft, movable partitions mounted upon said fixed partitions having perforations therein adapted to register with the perforations in said fixed partitions and means for simultaneously operating said movable partitions to open and close said perforations.

2. A fire-partition for elevator-shafts and the like, comprising a plurality of non-combustible plates having elongated openings therein and intervening bars, said plates being slidably secured, face to face, and the width of the openings therein being substantially equal to the width of as many bars as there are plates, less the width of one bar,

and means for shifting the plates to bring the openings opposite each other, or the bars opposite the openings to close the same.

3. In a fire-partition the combination of one 5 fixed and two movable plates, each having rectangular openings and intervening bars between said openings, said bars being of a width substantially equal to one-half the width of said openings.

10 4. In a fire-partition for elevator-shafts, the combination with a fixed partition-plate provided with a series of perforations, of a movable partition-plate provided with a series of 15 perforations adapted to register with those of the fixed plate, racks secured to the ends of said movable plate, a rock-shaft mounted in fixed bearings and gears fixed to said rock-shaft adapted to engage said racks.

5. In a fire-partition, the combination with 20 a fixed plate, of a movable plate mounted on either side of said fixed plate, rectangular openings in all of said plates forming bars

between said rectangular openings of a width substantially equal to one-half the width of said openings, and means for connecting said 25 movable plates whereby they are caused to move in opposite directions to open and close said openings.

6. In a fire-partition for elevator-shafts, the combination with a plurality of perforated 30 plates fixed to sides of the elevator-shaft, of movable perforated plates slidably mounted on said fixed plates, shafts mounted on the sides of said elevator-shaft in geared connection, and connections between said shafts and 35 said movable plates.

In testimony whereof I have signed my name to this specification in the presence of two subscribing witnesses.

JESSE W. RENO.
